INVENTOR.
Frank Mullin
BY *Chester W. Braselton*
ATTORNEY

UNITED STATES PATENT OFFICE.

FRANK MULLIN, OF ELYRIA, OHIO, ASSIGNOR TO THE WILLYS-OVERLAND COMPANY,
OF TOLEDO, OHIO, A CORPORATION OF OHIO.

DRILL.

Application filed February 14, 1919. Serial No. 276,967.

To all whom it may concern:

Be it known that I, FRANK MULLIN, residing at Elyria, county of Lorain, and State of Ohio, have invented certain new and useful Improvements in Drills, of which I declare the following to be a full, clear, and exact description.

This invention relates to drills, and more particularly to drills adapted for the purpose of boring metal articles.

One object of the invention is to provide a device of this character, wherein the cutting elements are capable of radial adjustment with respect to the drill.

15 A further object of the invention is to provide a device of this character having means for firmly clamping the cutting elements in a plurality of adjusted positions with respect to the drill.

20 A further object of the invention is to provide a device of this character, having means for securing a relatively fine adjustment of the cutters, and for varying this adjustment from time to time as occasion may require.

25 A further object of the invention is to provide a device of this character which is of simple construction and efficient in operation.

Further objects of the invention relate to 30 economies of manufacture and details of construction, as will hereinafter appear from the detailed description to follow.

The objects of the invention are accomplished in one instance by the devices and 35 means described in the following specification, but it is evident that the same may be varied widely without departing from the scope of the invention as pointed out in the appended claims.

40 A structure constituting one embodiment of the invention, which may be the preferred, is illustrated in the accompanying drawing forming a part hereof, in which:

Figure I is a side elevational view of the 45 improved drill, illustrating the relative position of the operating parts.

Figure II is a view, partially in longitudinal section of the improved drill showing the relative position of the operating parts, 50 and the means for clamping the cutting elements in position.

Figure III is an end view of the drill, illustrating the relative position of the cutting elements with respect to the head portion 55 of the drill.

Figure IV is a view, partially in section, showing the relative location of the cutting elements with respect to the grooves.

Figure V is an end view of a modified form of drill, which is designed to employ 60 but one cutting element.

Figure VI is a sectional view, taken along the line VI—VI of Figure V, and illustrating the relative position of the various parts of the mechanism. 65

Referring to the drawings, similar reference characters designate corresponding parts throughout the several views, and the sectional views are taken looking in the direction of the small arrows at the ends of the 70 section lines.

In the embodiment of the invention illustrated herewith, 10 indicates the main body portion of the drill which is provided with a shank 11, adapted to be carried by a head 75 (not shown). A bearing shoulder 12 is provided at the point where the spindle portion joins the main body portion of the drill, and the body portion is provided with one or

more spirally fluted clearing grooves 13, 80 which extend spirally of the longitudinal axis of the drill and are formed in the exterior surface of the body portion, one of these grooves preferably being associated with each cutting element. Spaced from the spiral fluted clearing grooves and formed in the body portion of the drill are one or

more spirally extending oil grooves 14, each of these grooves being preferably spaced an equal distance from the two adjacent spiral 85 clearing grooves 13, when two or more of the clearing grooves are employed. The spirally extending clearing grooves 13 serve to provide a means for conducting the material

which is cut away by the cutting elements 90 outwardly and away from the material to be operated upon, while the oil grooves 14 serve to provide means for conducting a lubricat-

ing oil to the cutting elements, for the purpose of properly lubricating the cutting 95 faces thereof while they are cutting the material.

The head portion 15 of the drill is provided with one or more radial grooves 16 extending from the central portion of the 100 drill to the circumference thereof, the grooves preferably being diametrically arranged with respect to each other. A cutting element 17 provided with a cutting edge 110

18 is slidably positioned within each of the

grooves 16 in such a manner that the cutting edge thereof extends outwardly toward the outer surface of the drill where it is adapted to contact with the material which is to be operated upon. Each of the cutting elements 17 is provided with a beveled portion 19 upon the end opposite the cutting edge 18, for a purpose which will presently be described.

10 A central opening 20 is provided in the end portion of the drill, the outer extremity of which is smooth, while the inner extremity 21 is provided with an interior thread for the purpose of engaging with a thread 15 formed upon the reduced portion 22 of a bolt 23. The central portion of the bolt 23 is of such size as to be adapted to fit snugly within the enlarged smooth portion of the opening 20, while one end thereof is reduced 20 and is provided with an exterior thread so as to be capable of being adjustably positioned within the threaded portion 21 of the opening. Adjacent the central enlarged portion 23 of the bolt, and positioned upon the 25 opposite side thereof from the reduced portion 22 is a shoulder portion 24, which is beveled and is adapted to contact with the beveled ends 19 of the cutting elements 17. Extending from the shoulder portion 24 of 30 the bolt is a reduced end portion 25, which is provided with external threads thereon so as to receive a locking nut 26 and hold the same in position. A clamping washer 27 is preferably interposed between the cutting 35 elements 17 and the locking nut 26 which is adapted to be firmly clamped between the locking nut and the cutting element when the nut is threaded upon the bolt a sufficient distance to properly hold the cutting elements in position.

40 The bolt 23 is provided with a groove 28 formed in the outer end thereof for the purpose of threading the bolt a sufficient distance within the reduced interiorally threaded portions 21 of the opening so as to suitably position the cutting elements radially of the drill. It will be noticed that each of the spiral clearing grooves 13 communicates with the head portion of the drill 45 at a point near where the cutting edge 18 of one of the cutters engages with the material which is to be operated upon, whereby they are most advantageously positioned for the purpose of removing that portion of the 50 material which is cut away.

55 In the modified form of the invention illustrated in Figures V and VI, a single cutting element 29 is employed, while a block 32 is firmly secured in the opposite groove 16 by means of a screw 30 and pin 31, which serve to firmly position the block and securely hold the same within the groove, thus providing a means for supporting the adjusting bolt 23 in proper position. The bolt 23 employed in this modification is similar in all

respects to that previously described and the inner edge 33 of the block 32 is squared so that the face thereof, which is presented to the shoulder portion 24 of the bolt 23, is parallel to the longitudinal axis of the bolt 70 and contacts with the extreme outer edge of the shoulder, thereby serving as a support for centering the bolt and maintaining the same in proper position for securing the necessary radial adjustment of the cutting element 29 75 as the bolt 23 is adjusted within the opening 20 formed in the end of the drill. It will be noticed upon reference to Figure V that as only one cutting element is employed, it is found necessary to use only one of the 80 spirally fluted grooves 35 formed in the outer face of the drill, but two oil grooves 36 are provided, each of which is spaced 120° from the cutting edge of the cutting element.

85 In the operation of this device the shank 11 is inserted in a drilling machine spindle (not shown), by which the drill is supported in the usual manner. The bolt 23 is adapted to be adjustably positioned within the opening 20 by means of the reduced threaded portion 22 being properly threaded within the threaded extension 21 of the opening 20. The bolt 23 is inserted a sufficient distance 90 so that the shouldered portion 24 bearing against the beveled end 19 of the cutting element forces the cutting element radially outward a sufficient distance to properly operate upon the material to be cut. The bolt 23 thus having been properly positioned in such a manner as to correctly adjust the cutting element, the locking washer 27 is placed in position upon the bolt with the inner face thereof bearing against the outer portion of the cutting elements and the lock nut 26 is then threaded upon the outer 95 end of the bolt 23, which when firmly threaded against the outer surface of the washer 27 clamps the same securely against the cutting elements, and thereby firmly secures the cutting elements in proper position. If 100 at any time it is desired to change the adjustment of the cutting elements, such change can be accomplished by releasing the lock nut 26, whereupon the bolt 23 may be adjusted within the opening formed in the end of the drill and again clamped in position by tightening the lock nut 26.

105 The manner of adjusting the cutter 29 in the modification shown in Figures V and VI, is similar to that employed in the modification illustrated in Figure I to IV inclusive. In this modification, however, the opposite portion of the beveled shoulder 24 from that which engages with the cutting element 29 is adapted to bear at all times 110 against the inner edge of the block 32, so as to properly retain the bolt 23 in its central position in the same manner as it would be accomplished if two opposed cutting elements were employed.

While I have shown and described in considerable detail a specific embodiment of my invention, it is to be understood that this showing and description is illustrative only, and for the purpose of rendering my invention more clear, and that I do not regard the invention as limited to the details of construction illustrated or described, nor any of them, except in so far as I have included such limitations within the terms of the following claims, in which it is my intention to claim all novelty inherent in my invention broadly as well as specifically.

What I claim as new and desire to secure by Letters Patent is:—

1. A drill provided with a central opening therein threaded throughout a portion of its extent, cutters carried by the drill, a threaded member positioned within the internally threaded opening and provided with a beveled portion adapted to contact with the cutters and limit the radial movement of the same relative to the drill, a washer bearing against one side of the cutters, and common means acting through said washer for holding the cutters against removal and locking the threaded member against movement.

2. In a drill having an internally threaded opening formed in one end thereof, radially positioned cutters having their inner ends located adjacent the central opening, a member threaded within the internally threaded opening in the drill and provided with a beveled portion adapted to engage the inner ends of the cutters and limit the inward movement of the same, a washer carried by the said member and bearing against

the cutters, and a nut threaded upon the said member and adapted to bear against the said washer to hold the cutters against movement and at the same time lock the threaded member in adjusted position.

3. A drill bar having a groove cut across the end thereof, a cutter slideable in said groove, said bar having an axial bore intersecting said groove, a bolt threadedly engaging the said bore inwardly of the groove, and provided with a conical portion bearing against the inner end of the cutter, a washer surrounding said bolt and bearing against the said cutter and a nut threaded upon the outer end of said bolt and adapted to bear against the washer to force the latter into locking engagement with the cutter.

4. In a drill bar having a groove cut across the end thereof, a cutter slideable in said groove, said bar having an axial bore intersecting said groove, said bore being smooth for a portion of its length inward of the groove, and the inner end of the bore being constricted and threaded, a bolt having a smooth portion for fitting within the smooth portion of the bore and an inner constricted end threaded into the threaded portion of the bore, said bolt near its outer end having a conical portion adapted to bear against the inner end of the cutter and means on the bolt for locking the cutter in adjusted position and the bolt against movement.

In testimony whereof, I affix my signature.

FRANK MULLIN.
